US00D967417S

(12) **United States Design Patent** (10) Patent No.: **US D967,417 S**
(45) Date of Patent: **** Oct. 18, 2022**

(54) **CATHETER**

- (71) Applicant: **DENTSPLY IH AB**, Mölndal (SE)
(72) Inventors: **Gustaf Ljunglöf**, Gothenburg (SE);
Niklas Dahlberg, Lerum (SE); **Anna Kylberg Malmborg**, Vallda (SE)
(73) Assignee: **DENTSPLY IH AB**, Mölndal (SE)
(**) Term: **15 Years**
(21) Appl. No.: **29/808,069**
(22) Filed: **Sep. 16, 2021**

(57) **CLAIM**

The ornamental design for a catheter, as shown and described.

DESCRIPTION

FIG. 1 is a perspective view of an embodiment of the catheter;

FIG. 2 is a top plan view thereof;

FIG. 3 is a bottom plan view thereof;

FIG. 4 is a front elevation view thereof;

FIG. 5 is a right side elevational view thereof;

FIG. 6 is a left side elevational view thereof; and,

FIG. 7 is a rear elevational view thereof.

The broken lines in the figures show portions of the catheter that form no part of the claimed design.
